UNITED STATES PATENT OFFICE.

JOHN W. SEIBERT AND JAMES WARREN RILEY, OF GALESBURG, ILLINOIS.

NON-SKID MUD-SHOE FOR AUTOS.

1,131,560.

Specification of Letters Patent.

Patented Mar. 9, 1915.

Application filed December 24, 1914. Serial No. 878,956.

To all whom it may concern:

Be it known that we, JOHN W. SEIBERT and JAMES W. RILEY, citizens of the United States, residing at Galesburg, in the county 5 of Knox, State of Illinois, have invented a new and useful Non-Skid Mud-Shoe for Autos, of which the following is a specification.

The device forming the subject matter of 10 this application is a shoe or protector for vehicle tires.

The invention aims to provide novel 15 means for reinforcing the transverse traction cleats, the said means constituting also places of attachment for the connecting links.

It is within the scope of the disclosure to 20 improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

In the drawing:—Figure 1 shows in side elevation a wheel equipped with the device forming the subject matter of this application; Fig. 2 is a top plan of one of the constituent members of the protector; Fig. 3 is a cross section on the line 3—3 of Fig. 1; Fig. 4 is a cross section on the line 4—4 of Fig. 1.

The tire protector herein disclosed 40 comprises a plurality of rigid members preferably fashioned from iron or steel, each of the said members including a trough-shaped body 1, the body 1 being equipped with a single pair of transverse traction cleats 2 which extend as shown at 3 to the extreme 45 longitudinal edges of the body 1, the cleats 2 being spaced from the ends of the body 1 to form tire protecting extensions 5, there being longitudinal ribs 6 formed integrally

with the cleats 2 and with the extensions 5, 50 the ribs 6 being located at the extreme ends of the extensions and at the extreme longitudinal edges of the extensions, the outer faces of the ribs merging unbrokenly into the outer faces of the cleats 2 as shown at 7. 55 The ribs 6 are provided with longitudinal slots 8 receiving the ends of links 9. Pivot elements 10 pass through the end portions of the ribs 6 and through the ends of the links 9 thereby to assemble the constituent 60 members of the protector pivotally together. If desired, one or more of the links 9 may be replaced by turnbuckles 11 adapted to tighten up the protector about the tire. At intervals, the flexible elements 12 may connect opposed portions of the trough-shaped 65 protecting elements, the securing elements 12 being of the hook and eye construction shown in Fig. 1 or being of any other desired form. The longitudinal ribs 6 exercise a double function. They serve at once 70 to reinforce the transverse cleats 2 and they afford strong reinforcements, adapted to be slotted as at 8 for the reception of the links 9. Owing to the fact that the ribs 6 are 75 located at the extreme longitudinal edges of the body 1, but do not extend entirely across the body 1, transversely, both faces of the cleats 2 are made effective. The extensions 5, protruding beyond the transverse 80 ribs 6, act as tire protecting elements and should any rib 6 ride off a stone or other obstruction, such obstruction will be engaged by the extensions 5, the tire 14 thus being protected. 85

Having thus described the invention, what is claimed is:—

A tire protector comprising a plurality of rigid members, each including a trough-shaped body, the body being equipped with 90 a single pair of transverse traction cleats which extend to the extreme longitudinal edges of the body, the cleats being spaced from the ends of the body to define tire protecting extensions, there being transversely 95 spaced longitudinal ribs formed integrally with the cleats and with the extensions and at the extreme longitudinal edges of the ex-

tensions, and at the extreme ends of the extensions, the outer faces of the ribs merging unbrokenly into the outer faces of the cleats, the ribs having longitudinal slots; links terminally mounted in the slots; and pivot elements passing through the links and entering the ribs.

In testimony that we claim the foregoing

Copies of this patent may be obtained for five cents each, by addressing the "Commissioner of Patents, Washington, D. C."

as our own, we have hereto affixed our signatures in the presence of two witnesses.
